Primary Examiner — Kelley Donnelly*(74) Attorney, Agent, or Firm* — Kirschstein, Israel, Schiffmiller & Pieroni, P.C.(57) **CLAIM**

The ornamental design for a watch display holder, as shown and described.

DESCRIPTION

FIG. 1 is an exploded, overhead, perspective view of a watch display holder according to my new design.

FIG. 2 is an overhead, perspective view thereof in one assembled display position.

FIG. 3 is an overhead, perspective view thereof in another assembled display position.

FIG. 4 is an overhead, perspective view thereof in still another assembled display position.

FIG. 5 is a perspective view from below in an additional assembled display position.

FIG. 6 is a perspective view from below in yet another assembled display position.

FIG. 7 is a perspective view from below in another assembled display position.

FIG. 8 is an overhead, perspective view thereof in another assembled display position.

FIG. 9 is an overhead, perspective view thereof in another assembled display position; and,

FIG. 10 is an overhead, perspective view thereof in still another assembled display position.

The broken lines showing is included for the purpose of illustrating environment and forms no part of the claimed design.

1 Claim, 10 Drawing Sheets(56)
